DESIGN FOR A PLASTIC SHOE HEEL

Earl S. Tupper, Leominster, Mass.

Application October 7, 1940, Serial No. 95,683

Term of patent 7 years

To all whom it may concern:

Be it known that I, Earl S. Tupper, a citizen of the United States, residing at Leominster, in the county of Worcester and State of Massachusetts, have invented a new, original, and ornamental Design for a Plastic Shoe Heel, of which the following is a specification, reference being had to the accompanying drawing, forming part thereof.

Fig. 1 is a top plan view of a shoe heel showing my new design;

Fig. 2 is a side elevation thereof;
Fig. 3 is a rear elevation; and
Fig. 4 is a front elevation thereof.

I claim:
The ornamental design for a plastic shoe heel,
as shown.

EARL S. TUPPER,
